DESIGN FOR A RECORD HOLDER

Alfons M. Rauch, New York, N. Y., assignor to Fabricspray, Inc., Long Island City, N. Y., a corporation of New York

Application May 16, 1942, Serial No. 106,920

Term of patent 7 years

To all whom it may concern:

Be it known that I, Alfons M. Rauch, a citizen of Germany residing at New York, in the county of New York and State of New York, have invented a new, original, and ornamental Design for a Record Holder, of which the following is a specification, reference being had to the accompanying drawing, forming part thereof.

Fig. 1 is a top plan view of a record holder showing my new design;

Fig. 2 is a side elevational view of the same; and

Fig. 3 is an end elevational view of the record holder.

The characteristic features of my design reside in the portions shown in full lines in the drawing.

I claim:

The ornamental design for a record holder or similar article, as shown and described.

ALFONS M. RAUCH.
